UNITED STATES PATENT OFFICE.

JAMES W. PRICE, OF TULSA, OKLAHOMA, ASSIGNOR TO TULSA INVENTION COMPANY,
OF TULSA, OKLAHOMA, A CORPORATION.

HAIR CLIPPER.

Application filed November 16, 1922. Serial No. 601,376.

To all whom it may concern:

Be it known that I, JAMES W. PRICE, a citizen of the United States, and a resident of Tulsa, in the county of Tulsa and State 5 of Oklahoma, have invented certain new and useful Improvements in Hair Clippers, of which the following is a specification.

This invention relates to hair clippers and has for its object the provision of a power 10 driven device for cutting hair and provided with an oscillating arm extending the entire length of the device for operating the usual movable cutter whereby a more effective cutting stroke of the cutter is had.

15 A further object of the invention is the provision of a power driven device having an oscillating arm for actuating the movable cutter and movable at one end through an opening in a grease packed casing, with 20 means on the arm coating with the wall of the casing adjacent the opening to prevent loss of grease from said casing.

Another object of the invention is the provision of a power driven device for cutting hair which is enclosed within a casing and equipped with an operating shaft mounted in a bearing block, with said block and shaft being removable as a unit from the casing.

30 Other objects and advantages will become apparent during the course of the following description.

The invention is illustrated by way of example in the accompanying drawings, in 35 which,

Figure 1 is a view in perspective of the assembled hair clipper.

Figure 2 is a plan view of the same with the cover removed.

40 Figure 3 is a plan view of a hair clipper with the cover and operating arm removed.

Figure 4 is a view in perspective of the oscillating arm for actuating the movable clipper.

45 Figure 5 is a view in perspective of the bearing block in which the driving shaft is mounted.

Referring to the drawings, 1 designates a casing having an extension 2 which is 50 adapted to support the cutter. Rigidly mounted within the casing 1 is a block 3, the height of which falls slightly short of the upper edges of the walls of the casing in order to provide a seat for the cover which is screwed upon said casing. One side of

the block 3 is cut away to form a pocket to receive a bearing block 4 in which is mounted a drive shaft 5. The drive shaft is provided at its inner end with a worm 6 while its outer end is adapted to be connected with a flexible shaft which is connected with a motor for driving the shaft 5. The block 4 is held to the casing 1 by means of a screw 7, the shaft 5 and block 4 being removable as a unit from the casing.

A gear 8 which meshes with the worm 6 is mounted upon a stub shaft 9 which is secured to the casing 1 by means of a nut 10. A pin 11, which is mounted eccentrically on the gear 8 is adapted to receive a perforated cross head 12 which is moved through an arc of a circle when the gear 8 is rotated. The gear 8 is mounted within a circular recess formed in the block 3. The casing 1 is provided with a passage 13 at 65 one end.

An oscillating arm 14 is provided with a pin 15 which is located in a recess 16 in the block 3 and at one end of a groove 17 formed longitudinally of the block. The 80 bearing block 4 is likewise provided with a groove 18 at one corner which is a continuation of the groove 17 and in which the arm 14 is adapted to oscillate. Adjacent the outer end, the oscillating arm 14 is 85 provided with a laterally projecting plate 19 having an elongated slot 20 which is adapted to receive the cross head 12. The plate 19 forms a shoulder 21 at its outer end which is adapted to engage the end wall 22 adjacent the opening 13 and cooperate with a lug 23 located upon the opposite edge of the arm 14 to prevent the loss of grease from the casing 1 when the angular portion 24 of the arm 14, which extends through the 90 opening 13, is oscillated through said opening, the lug 23 being movable in engagement with a portion of the end wall 22.

The angular portion 24 of the arm 14 is provided with an enlargement 25 having a 100 passage 26 therein which is designed to receive the inner end of the thumb screw 27 which is adapted to lock one end of the casing and a stationary blade 28 to said casing. The extreme outer end of the oscillating arm is provided with an upstanding lug 29 which is adapted to be received within a slot located on the inner end of the oscillating blade 30.

The operation of my device is as follows:

When the shaft 5 is rotated by means of the flexible shaft 31 the worm 6 is rotated which, being in mesh with the gear 8 rotates said gear. The cross head 12 being mounted eccentrically on the gear 8 is moved in a circle causing oscillation of the arm 14 since the cross head 12 slides within the elongated opening 20 in the lateral extension 19 of the arm 14. The angular portion 24 of the arm 14 oscillates in the opening 13 at one end 22 of the casing with the lug 23 and the shoulder 21 engaging the wall 22 adjacent the opening 13 at all times and preventing loss of grease from the casing. The casing at all times is packed with grease so that the operating parts will be thoroughly lubricated. Oscillation of the arm 14 causes oscillation of the movable blade 30.

What I claim is:

- 20 1. A hair clipper comprising a casing provided with an opening at one end, a bearing block removably mounted within the casing, a shaft provided with a worm rotatably mounted in the bearing block and removable with said block as a unit from the casing, an oscillating arm having one end pivotally mounted at one end of the casing and projecting through the opening at the other end of said casing, a plate integrally formed with and projecting laterally from the oscillating arm, said plate being provided with an elongated slot, a gear in mesh with the worm, a pin eccentrically mounted on the gear, a cross head loosely mounted on the pin and movable in the slot whereby the arm is oscillated, means on the arm coacting with the wall of the casing adjacent the opening in the casing for preventing loss of lubricant from said casing, and a cutter operated by the oscillating arm.
- 25 2. A hair clipper comprising a casing provided with an opening at one end, a shaft mounted for rotation in the casing and provided with a worm, an oscillating arm having one end pivotally mounted at one end of the casing and projecting through the opening at the other end of the casing, a

plate integrally formed with and projecting laterally from the oscillating arm, said plate being provided with an elongated slot, a gear in mesh with the worm, a pin eccentrically mounted on the gear, a cross head loosely mounted on the pin and movable in the slot whereby the arm is oscillated, and a cutter operated by the oscillating arm. 50

3. A hair clipper comprising a casing provided with an opening at one end, a shaft mounted for rotation in the casing and provided with a worm, an oscillating arm having one end pivotally mounted at one end 60 of the casing and projecting through the opening at the other end of the casing, a plate integrally formed with and projecting laterally from the oscillating arm, said plate being provided with an elongated slot, a gear in mesh with the worm, a pin eccentrically mounted on the gear, a cross head loosely mounted on the pin and movable in the slot whereby the arm is oscillated, and a cutter operated by the oscillating arm. 65

4. A hair clipper comprising a casing provided with an opening at one end, a block rigidly mounted in the casing having an elongated groove, and a perforation at one 70 end of the slot, an oscillating arm mounted in the groove and provided with a depending pin projecting into the perforation, a lug projecting laterally from one edge of the arm and a slotted plate projecting laterally from the opposite edge of the arm, said lug and plate coacting with the wall of the 75 casing adjacent the opening for maintaining the opening closed against loss of lubricant from the casing, a cross head mounted in the slot in the plate, means for actuating the cross head whereby the arm is oscillated, and a cutter operated by the oscillating arm. 80
